Primary Examiner — Stacia A Cadmus*(74) Attorney, Agent, or Firm* — Epiphany Law, LLC(57) **CLAIM**

The ornamental design for a vehicle wheel, as shown and described.

DESCRIPTION

FIG. 1 is a perspective view of a vehicle wheel, showing my new design;

FIG. 2 is a front view thereof;

FIG. 3 is another perspective view thereof;

FIG. 4 is a perspective view of a second embodiment of a vehicle wheel showing my new design;

FIG. 5 is a front view of FIG. 4; and,

FIG. 6 is another perspective view of FIG. 4.

In the drawings the broken lines depict portions of the wheel that form no part of the claimed design.
